UNITED STATES PATENT OFFICE.

WARREN F. DREW, OF NEW YORK, N. Y., ASSIGNOR TO HARRIS HAMMOND, OF NEW YORK, N. Y.

LOCK FOR VALVES.

1,115,792.

Specification of Letters Patent.

Patented Nov. 3, 1914.

Application filed December 13, 1913. Serial No. 806,409.

To all whom it may concern:

Be it known that I, WARREN F. DREW, a citizen of the United States, residing at 17 East Fifty-ninth street, care of Lester Vonda, New York city, in the county of New York and State of New York, have invented certain new and useful Improvements in Locks for Valves, of which the following is a specification.

10 This invention relates to locks for valves and the like, and its novelty consists in the construction and adaptation of the parts, as will be more fully hereinafter pointed out.

Where valves of comparatively large size 15 are employed in exposed situations, such as in pipe lines for oil and water systems, two difficulties are met with in their use. One is the opening of the valve by unauthorized persons animated by mischievous or other 20 motives, and the other is the difficulty of opening such a valve by an authorized person where the pressures are great or other conditions render it difficult. I have sought to overcome both of these difficulties by providing a simple and efficient means for opening and closing the valve and locking it in 25 either position.

In the drawings in which there is illustrated a device embodying the invention, 30 Figure 1 is a top plan view of the device; Fig. 2 is a transverse vertical section on the plane of the line 2—2 in Fig. 1; Fig. 3 is a side elevation, and Fig. 4 is a detail showing a protecting plate for the gears.

35 In the drawings, 10 represents a casing of a valve and 20 a plug or body adapted to be rotated therein. Any usual form of valve in which a plug provided with apertures is adapted to be revolved within a casing provided with apertures with which the plug 40 apertures may register is adaptable for use with my invention, and the precise form, size, shape and material of these co-operative parts are immaterial so far as my present invention is concerned.

The casing is provided at any convenient place with a bracket 11 secured to, or made integral therewith, and having two laterally extending apertured members 12 and 13, between which is a collar 14 provided with two holes opposite each other and adapted to receive a pin indicated at 15. At its upper edge the casing is recessed to receive a packing ring 16, and at its lower end it is turned at 17 and provided with an annular

flange 18 externally threaded to receive a cap 19 of any usual suitable form.

The casing is provided with the usual annular flanges 100 having plane external angular surfaces and threaded internally to receive the conduits 101, 102, the passageway through which the valve is adapted to control.

The plug 20 is adapted to fit snugly within the casing 10. At its lower end it is restricted to form a neck 21 fitting within the inturned end 17 of the casing and is provided with a washer 22 between it and such end. It is further restricted at 23 and threaded externally to receive a tightening nut 24 whereby it may be adjusted within the casing. At its upper end it is expanded to form a cylindrical head 25 which is recessed at a proper place to receive the packing ring 16, and the periphery of the head is provided with gear teeth 26 projecting beyond the casing and forming a large cylindrical gear. Above the head 25 and secured to, or made integral therewith, is a lug 27 having two central bores 28 and 29 at right angles to each other.

Adapted to pass through the collar 14 is a stub shaft 30 expanded at 31 to form a head adapted to overlap or rest upon the head 25 of the plug and the upper end of which is restricted to form a lug 32 having a central bore 33. The head 31 overlapping the head 25 prevents the withdrawal of the plug from the casing. The pin 15 serves to secure the shaft to the collar 14. Secured on the shaft by a feather 35, or other suitable means, is a pinion 36 adapted to mesh with the gear 26 and to rotate it.

A relatively long lever 40 is adapted to slidably engage the pinion lug 32 and to pass through the aperture therein. It is provided at one end with an annular flange or projection 41 of greater diameter than this aperture to stop its movement in one direction and with a transverse pin 42 to stop its movement in the opposite direction. The aperture or bore 28 in the gear lug 27 is made large enough to permit of the passage of the pin 42. A hole 43 is made in the end of the lever 40 which projects beyond the lug 27 when the lever is in the position shown in Fig. 3, and through this hole is passed a hasp 45 of a padlock 46.

The flange 31 is adapted to shield the teeth of the pinion from injury. The gear

is similarly protected by a flange 47 overlapping its teeth 26 (see Fig. 4) and either made integral with the body 25 of the gear or secured thereto in any suitable manner, 5 for instance, by screws, indicated at 28. The operation of the device is as follows: When the parts are in the position shown in Fig. 2 the rotation of the lever 40 by hand will turn the pinion lug 32 and the pinion 10 36, and the latter being in mesh with the gear 25, the gear and the plug to which it is secured or with which it is made integral, is radially rotated no matter how large it may be and how difficult it might be to effect 15 such a rotation by hand. As will be readily understood the lever 40 is long enough to afford a very effectual leverage upon the pinion lug. If the lever 40 is slid into the position shown in Figs. 1, 4 and 3, it is 20 quite obvious that the lug 32 cannot be rotated and that the plug of the valve will remain fixed in whatever position it may be at the time that the lever is put through another one of the bores in the lug 27. The 25 padlock 46 affords a method of locking the lever into that inoperative position as will be seen in Fig. 3. Obviously, if the hasp of the padlock is put through the aperture 43 in the lever 40 when this aperture is any 30 where between the lug 32 and the lug 27, or if the hasp of the padlock is put through the bore 28 or the bore 29 of the lug 27 the lever 40 can be operated to rotate the pinion and consequently the gear and the valve plug and 35 its operation cannot be prevented. In other words, the padlock affords a means in connection with the aperture 43 and bores 28 and 29 of locking the device either in an operative or an inoperative position. The pin 40 42 which can freely pass through the bores 28 or 29 in the plug 27 but cannot pass through the corresponding bore in the lug 32, is provided for the purpose of preventing the removal of the lever from engagement 45 with the lug 32 and its consequent liability to loss.

What I claim is:

1. The combination with a valve comprising a plug and casing, of means for rotating the plug with respect to the casing, including a gear secured to the plug and a pinion adapted to mesh with such gear and carried by the casing and means for rotating the pinion, which means is also adapted to engage a part of the plug to lock it in either open or closed position and consists of a lever adapted to be manually operated and to slidably engage the pinion.
2. The combination with a valve comprising a plug and casing, of means for rotating the plug with respect to the casing, including a gear secured to the plug and a pinion adapted to mesh with such gear and car-

ried by the casing and means for rotating the pinion, which means is also adapted to engage a part of the plug to lock it in either open or closed position and consists of a lever adapted to be manually operated and to slidably engage the pinion and the plug.

3. In combination, a valve casing, a plug 70 adapted to be rotated with respect thereto by a gear, a pinion mounted on a shaft adapted to revolve in bearings relatively fixed with respect to the casing and which pinion is adapted to mesh with the gear, an apertured 75 lug adapted to rotate with the pinion and means for rotating it including a vise-handle lever adapted to slidably engage the lug through its aperture and which lever is also adapted to engage a portion of the gear to 80 prevent its rotation in either open or closed position.

4. In a device of the character described, a valve casing provided with a bracket, a shaft adapted to be supported thereby and 85 carrying a pinion, a plug adapted to be rotated within the casing, a gear adapted to rotate the same and to be moved by the pinion, in combination with means for rotating the pinion and which means is also 90 adapted to prevent the rotation of the pinion and gear including an apertured lug on the pinion, a second apertured lug on the gear, and a lever adapted to slidably engage both lugs and which, when it engages the pinion 95 lug, may be used as a handle to turn it and when it engages the gear lug may be used as a stop to lock it in either open or closed position.

5. In a device of the character described, 100 a valve casing a plug adapted to rotate therein, a gear secured to the plug, a pinion mounted on the casing and adapted to mesh with the gear, and a removable shaft secured to the pinion provided with an enlarged head, said head adapted to entirely cover the pinion and a portion of the plug in combination with a device for moving the pinion including a lug on the shaft provided with a central bore and a rod adapted 110 to fit therein, and a device for preventing the movement of both the pinion and the gear, including a lug on the gear provided with central bores adapted to receive the rod, and means for locking the latter in 115 either a position to permit or prevent fluid flow through the plug consisting of a hole in the rod, and a padlock, the hasp of which is adapted to pass through the hole.

In testimony whereof I affix my signature 120 in presence of two witnesses.

WARREN F. DREW.
